UNITED STATES PATENT OFFICE.

RUDOLPH KLEINMAN, OF NEW YORK, N. Y., ASSIGNOR TO BOZART LIGHTING CO., OF NEW YORK, N. Y.

DESIGN FOR AN ARM FOR A LIGHTING-FIXTURE.

60,043.

Specification for Design.

Patented Dec. 20, 1921.

Application filed April 19, 1921. Serial No. 462,710. Term of patent 3½ years.

To all whom it may concern:

Be it known that I, RUDOLPH KLEINMAN, a citizen of the United States, residing at New York, in the county and State of New York, have invented a new, original, and ornamental Design for an Arm for a Lighting-Fixture, of which the following is a specification, reference being had to the accompanying drawings, forming part thereof.

Figure 1 is a front view of the socket showing my new design; and Fig. 2 is a side view of the socket showing my new design.

I claim:—

The ornamental design for an arm for a lighting fixture as shown.

In testimony whereof I have affixed my signature in presence of two witnesses.

RUDOLPH KLEINMAN.
